[57] CLAIM

The ornamental design for an electric saw, as shown and described.

DESCRIPTION

FIG. 1 is a front, top and right side perspective view of an electric saw showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and

FIG. 7 is a rear elevational view thereof.

The characteristic feature of the design resides in the existence of four parallel, thin slits in the semicircular saw cover which are sized to and complement (1) the ribs at the rear portion of the gear case and motor housing, (2) transverse slots within the front and along the side of the motor housing, and (3) ribs on the front oblique portion of the continuous loop handle in front of the rearwardly spaced, parallel oblique handle grip portion.
